UNITED STATES PATENT OFFICE

PORTIS H. MITCHELL, OF DALLAS, TEXAS

GAUGE

Application filed March 18, 1927. Serial No. 176,467.

This invention relates to measuring instruments, and more particularly to gauges for use in determining measurements on worn car axle journals and the like.

5 One of the objects of the invention is the provision of a new and improved device for gauging fillet wear on worn car axles.

Another object of the invention is the provision of a new and improved device for 10 gauging the fillet wear of car axles, determining the over-all length of the journals, and for indicating the radial wear on said axle journal.

Other objects of the invention are the provision of a new and improved gauge that is 15 simple in construction, cheap to manufacture, easily assembled, and one with which the different measurements may be readily taken and the readings made with ease and facility.

20 Other and further objects and advantages of the invention will appear from the following description taken in connection with the accompanying drawings, in which

Fig. 1 is a side elevation of the device, showing car axles of different sizes in dotted lines;

Fig. 2 is a section on line 2—2 of Fig. 1; and

Fig. 3 is a vertical section of a portion of a car journal, with a worn fillet and with 30 a portion of the gauge in position thereon.

The journals of car axles become worn by use,—this is especially true of the fillet at the inner end of the journal. It is the common practice when the fillets of car axle 35 journals become worn to restore their proper contour by turning the same. In some instances the principal wear is on the intermediate portion of the fillet whereby the fillet shoulder is more nearly straight or perpendicular, while in other cases the wear occurs on its outer surface, thereby lengthening the fillet shoulder. In either case, the journal may be turned to restore the proper contour to the fillet if such turning will result in a

45 journal meeting the requirements of the American Railway Association which govern such constructions.

The construction of car axle journals is in conformity to certain rules which prescribe 50 the tolerances permissible in their construc-

tion. If a worn car axle journal can be turned within the limits or measurements laid down by those rules, the journal is turned and the axle replaced. If, on the other hand, this cannot be done, the axle must be discarded, 55 and a new one inserted in its place.

The purpose of the present invention is to provide a measuring instrument for measuring worn axle journals to determine whether the same are of sufficient dimensions to permit 60 them to be turned and the proper curvature of the fillets restored without exceeding certain dimensional limits that have been prescribed by the American Railway Association 65 for such constructions.

Referring now to the drawings, on which is shown one embodiment of the invention, the reference character 10 designates the gauge which comprises a staff or measuring arm 11 having an enlargement at one end, at one or 70 both side edges thereof. As shown, it is enlarged at each side edge to form the lateral projections 12 and 13. The staff is also provided with an extension as at 14. The enlargements or projections are provided at 75 their outer edges with flat surfaces 15 and 16 that are parallel with each other and with the axis of said measuring arm 11. These parallel surfaces merge into surfaces 17 and 18 respectively which are curved to correspond to the curvature of the fillets on car 80 axle journals. The curvature at 17 is the same as the curvature of fillets of the smaller journals 19 indicated by the dotted lines and notations above the gauge in Fig. 1, and the curvature at 18 is the same as that of the 85 fillets of the larger axles 21, 22 and 23 shown by dotted lines superposed below the gauge and indicated by suitable notations in Fig. 1. These notations are the limits for turned, or 90 what is known as secondhand, axles.

These curved surfaces terminate opposite each other in a line at right angles to the axis of the staff 11. The staff is graduated both ways from this line, as indicated at 31 and 95 32. An indicator slide 33 slidably mounted on the staff 11 is provided with an index 34 for indicating the adjustment of said slide. The slide is held in adjusted position by any 100 suitable means as the spring-pressed friction

members 37 and 38 attached to said slide. The gauge in Fig. 1 is shown as being applied to the journal 21. The curved projection 18 is in contact with the fillet 35 and the outer end of the slide 33 abuts the inner surface of the collar 36. The index 34 indicates the length of the journal.

The fillets of car axle journals become worn by use. The fillets are said to be worn "straight" when their radius becomes shorter or their surface becomes more nearly perpendicular to the axis of the journal, and are said to be worn "long" when their radius becomes greater or their length increases, whereby they are more nearly parallel with the axis of the journal.

In Fig. 3 is shown a portion of an axle 24 provided with a journal 25 having its fillet 26 worn "straight". In order to restore the proper curvature a portion of the metal of the guard seat 27 must evidently be removed, which operation will increase the length of the journal.

Suitable means are provided for determining how much of the metal must be turned from the dust guard seat in order to restore the proper curvature to the fillet 26. Indicator members adjustably mounted on the enlargement are employed for this purpose. As shown, the enlargement in the staff is provided with an angular slot 41 for receiving the heads of indicator screws 42 and 43. These screws are preferably arranged at a substantially 45 degree angle to the axis of the staff, although it is understood they may be arranged at a different angle, if desired. The inner marginal walls of the angular slot 41 are graduated, as shown at 44 and 45. The screws 42 and 43 have enlarged heads which may be knurled and are preferably provided with disk-like indicator members or pointers 46 and 47. The pointers will indicate the distance between the curved surfaces 17 and 18 and the fillets, which, added to the length of the journal as indicated by the index 34, will give the length the journals will be when they have been turned and the proper curvatures restored to the fillets. For instance, in Fig. 3, the indicator 47 is half-way between the third and fourth marks 45, which means that if these marks are $\frac{1}{16}$ inch apart, three and one-half sixteenths must be added to the length of the journal in order to restore the proper curvature to the fillet 26.

If the fillet is worn "long" the curve 18 will engage the inner portion and the shoulder formed by the fillet and dust guard journal 27 will be spaced from the curved surface 18 of the gauge. This distance will be indicated at 32 on the extension which, added to the amount indicated by the index finger 34, will give the present length of the journal, and since the fillet is "long" this length will also be the length of the journal after it is turned.

Suitable marks or graduations are also pro-

vided for indicating the prescribed limits of the diameter of both new and second hand axles. In the form of the device shown, which will illustrate the principle of the device, the extension 12 is provided with two marks 51 and 52 which are parallel with the axis of the gauge. The mark 51 is in alignment with the surface of the dust guard journal when the axle 19 is new, and when the axle has been re-turned the mark 52 must not be below the surface of the dust guard. Consequently when the gauge is applied to worn axles that were $4\frac{1}{4} \times 8$ when new, the line 52 will indicate at once whether or not the axle must be discarded. If the mark 52 falls radially inwardly of the outer surface of the dust guard journal the car axle must be discarded. As shown, the axle 19 has reached the limit.

Similarly the projection or extension 13 is provided with three lines 53, 54 and 55 which are parallel with the axis of the gauge. The mark 53 indicates the limit for 11 inch journals, and the mark 54 the limit for 9 and 10 inch journals. The mark 55 indicates the normal line when these axles are new.

In the operation of the device, the gauge is placed on the journal with either the curved surface 17 or 18, depending on the size of the axle, in contact with the fillet and the slide 33 moved against the straight portion of the collar 36 of the journal, and the readings taken as indicated above. It will thus be apparent that at a glance the workmen can determine what will be the length and diameter of the axle when it has been returned to restore the proper curve to the fillet.

It is thought from the foregoing taken in connection with the accompanying drawings that the construction and operation of my device will be apparent to those skilled in the art, and that various changes in size, shape, proportion and details of construction may be made without departing from the spirit and scope of the appended claims.

I claim as my invention:

1. A measuring instrument for car axle journals comprising a staff having graduations thereon, an enlargement at one end of said staff having its outer surfaces curved to different radii to correspond to the curvature of fillets in car axle journals, said staff being extended beyond said enlargement and provided with graduations on the extended portion, said enlargement having lines thereon parallel with the axis of said staff for indicating the limit of radial wear on said journals.

2. A measuring instrument for car axle journals, comprising a staff having graduations thereon, an enlargement at one end of said staff having the forward portions of their edge surfaces curved to correspond to the curvature of fillets in car axle journals, said staff being provided with a graduated

extension for ascertaining the destined greater length of worn axle journals should the fillets be restored to their respective normal curvature.

3. A measuring instrument for car axle journals comprising a staff having graduations thereon, means on said staff for engaging the fillet of a car axle journal and conforming to the normal curvature of said fillet, means on said instrument including a graduated extension thereon for indicating the wear on said fillet and additional means for indicating the radial wear on said axle journal.

4. A gauge for car axle journals comprising a staff having a lateral extension at one end thereof, the periphery of said extension being curved to conform to the normal curve of the fillet of a car axle journal, and said staff being provided with a plurality of marks parallel with the axis thereof for indicating the diameter of car axle journals, and means including a graduated extension on said staff for determining the length of said journal between the dust guard seat and its inner end and the collar at its outer end.

5. A gauge for car axle journals for determining limits of diameters of car axles comprising a staff, projections extending laterally in opposite directions from one end portion of said staff, the periphery of each extension being curved to conform to the curvature of fillets of car axle journals of different types, and having a plurality of marks on each extension parallel with the axis of said staff for indicating the normal condition and limits of wear of car axle journals of different types.

6. A gauge for car axle journals comprising a staff having a portion curved at one end to conform to the curvature of a fillet on a car axle journal and having its opposite end graduated for determining the length of car axle journals, and a graduated extension on said staff extending longitudinally thereof beyond the curved portion thereof.

7. A gauge for car axle journals comprising a staff having a curved portion at one end, having a slot therein, a graduated extension beyond said curved portion, said staff having graduations on the marginal edge of said slot, a screw extending through said curved portion, and an index within said slot and threaded on said screw.

8. As an article of manufacture, a gauge for car axle journals comprising a staff, lateral extensions adjacent one end of said staff, said extensions having curved peripheral surfaces and being provided with slots, screws extending through said curved extensions, indices on the screws and movable in said slots, said extensions having graduations on the marginal edges of said slots opposite said

indices, and said staff having graduations on the end thereof opposite said extensions.

9. As an article of manufacture, a gauge comprising a staff having oppositely arranged lateral extensions on one end, the outer edges of said extensions being curved to different radii to conform to different fillet curves on car axle journals, said extensions being provided with slots having graduations on the marginal edge thereof, screws threaded through each extension, indices rigidly connected to said screws, said staff extending beyond said extension and being graduated, the opposite end of said staff being graduated, and a slide having an index thereon slidably mounted on said staff.

10. A gauge for worn car axle journals comprising a staff having a curved portion at one end and adapted to engage the fillet of a car axle journal, said curved portion having graduations thereon, indicator means adjustably mounted on said portion, a graduated extension beyond said curved portion, the other end of said staff being also provided with graduations and indicator means, said graduations and indicator means all cooperating to indicate the destined greater length of said journal should the fillet be restored to its normal curvature.

11. A gauge for worn car axle journals comprising a staff, one end of which is provided with means for engaging the fillet of a car axle journal, said end having graduations and indicator means thereon, a graduated extension beyond said curved portion, the other end of said staff being also provided with graduations and indicator means, said graduations and indicator means all cooperating to indicate the destined greater length of said journal should the fillet be restored to its normal curvature.

In testimony whereof I affix my signature.
